CLAIM

The ornamental design of a motion sensor light, substantially as shown and described.

DESCRIPTION

FIG. 1 is a front perspective view of a motion sensor light in accordance with the present invention;

FIG. 2 is a rear perspective view of the motion sensor light in FIG. 1;

FIG. 3 is a front side view thereof;

FIG. 4 is rear side view thereof;

FIG. 5 is left side view thereof;

FIG. 6 is right side view thereof;

FIG. 7 is a top side view thereof; and,

FIG. 8 is a bottom side view thereof.

The broken lines in the drawings represent portions of the motion sensor light that form no part of the claimed design.
